THREAD ROLLING APPARATUS

Charles Fassinger, Pittsburgh, Pa.

Application September 7, 1932, Serial No. 631,982

3 Claims. (Cl. 80—8)

My invention relates to thread-rolling apparatus and a method of rolling threads, particularly in the threading of bolts, screws, spikes and the like.

5 In the threading of blanks, it has been common practice to so roll or forge the shank of a blank that the over-all diameter of the threaded portion thereof will be somewhat greater than the diameter of the original blank, owing 10 to the fact that the threads are produced by pressing the teeth of the dies into the blank a distance less than the depth of the thread to be produced, the metal of the blank being displaced and caused to swell out into the spaces 15 between the teeth to form the tops of the threads. The over-all diameter of the finished article is therefore somewhat greater than the original diameter of the blank.

One object of my invention is to so thread a 20 blank that there will be no substantial displacement of the metal in a radially outward direction, and to produce threads which will be quite dense, and free from ruptures through excessive displacement of the metal contained within the 25 thread.

Another object of my invention is to provide 30 means for rolling threads by commencing at a point adjacent to the head of the blank and progressing toward the point or inner end thereof, instead of applying the threading teeth to the blank throughout substantially its entire length at the beginning of the thread-forming operation.

Another object of my invention is to provide 35 means for operating threading dies in such manner that danger of the blank slipping when initially engaged by the dies is minimized.

Still another object of my invention is to 40 simplify and improve generally the methods of and apparatus for rolling threads.

One manner in which my invention may be practiced is shown in the accompanying drawings, wherein Figure 1 is a plan view of a threading machine; Fig. 2 is a side elevational view 45 thereof; Fig. 3 is a cross sectional view, on an enlarged scale; Fig. 4 is a sectional view of a portion of the apparatus of Fig. 3, on a still further enlarged scale; Fig. 5 is a sectional plan view of the structure of Fig. 4; Fig. 6 is a view 50 similar to Fig. 4, but showing a completely threaded spike in position between the dies; Fig. 7 is a side elevational view showing one of the dies, and a partially rolled spike therein, 55 and Fig. 8 is a plan view showing the spike be-

tween the dies at a partially rolled stage, as in Fig. 7.

The apparatus is shown as mounted on a supporting frame or base 10 wherein a shaft 11 is journaled, the shaft being driven from any suitable source of power. The shaft 11 carries a pair of eccentrics 12 and 13, and a cam disc 14.

In the forward part of the frame 10 slide-ways 15 and 16 are provided, these slide-ways having suitable steel liner plates 17 and 18. The slide-way 15 is stationary while the slide-way 16 is periodically given some lateral movement by means of bell cranks 19 that have their inner ends pivotally connected to the slide-way 16 and their outer ends connected to a pull rod 20, the intermediate portions of the bell cranks pivotally connected to the frame 10. By this, the slide-way 16 has a lateral movement towards slide 15 at the beginning of each stroke, or cycle 75 of the crankshaft, and also, a lateral movement away from slide 15 at the end of each stroke or cycle of the crankshaft, so as to facilitate engagement of the blanks and release thereof by the dies.

80 Dies 21 and 22 are removably supported on slides 23 and 24 respectively, in any suitable manner, as by clamping brackets 25, the slides 23 and 24 being held in position on their slide-ways by brackets or clamping yokes 26 and 27 respectively. The slides 23 and 24, of course, have sliding movement on the slide-ways 15 and 16 as hereinafter described, to effect rolling of threads on blanks.

The slides 23 and 24 are operated by eccentric rods 28 and 29, respectively, that are in turn connected to the eccentrics 12 and 13, so that during rotation of the shaft 11, the slides 23 and 24, and the dies carried thereby, will be simultaneously reciprocated in opposite directions. 95

The cam disc 14 is of such contour that when the die 21 is in its foremost position and the die 22 at its rearmost position, as shown in Fig. 1, the rod 20 will be thrust forward to rock the cranks 19 in counter-clockwise directions to 100 thrust the slide-way 16 toward the slide-way 15, thus gripping the blank 31 between the die blocks 21 and 22, so that there will be no slipping of the blank about its axis at the beginning of the rolling operation.

105 At the instant the blank is gripped, as above-explained, the eccentrics 12 and 13 reach such positions that the die block 21 begins to move backwardly, and the die 22 forwardly, and such movements are continued until the thread has 110

been rolled on the blank 31. At the completion of the rolling operation, and preliminary to return movements of the dies, the raised surface of the cam disc 14 has passed out of engagement with the roller 33, whereupon the rod 20 is retracted by pressure of a spring 34 that operates against a nut 35 on the rod and a fixed stop shoulder 36 that is secured to the base of the machine, and which serves also as a guide for the rod 20. The bell cranks 19 will thereby be swung in a clockwise direction, shifting the slide-way 16 laterally from the slide-way 15. The dies are then returned by the eccentrics 12 and 13 to the positions shown in Fig. 1.

Another important feature of my invention resides in the form of the dies 21 and 22, which is shown more clearly in Fig. 7. These die blocks are complementally formed, and have their thread-forming teeth formed in somewhat the usual manner, except at the entrance of the dies, their toothed portions are in effect tapered, through the fact that the teeth are inclined or lie in diagonal lines, and are so positioned that only the upper portion of the blank is initially engaged by the teeth, the teeth being brought progressively into engagement with the shank as the rolling progresses.

The dies, during the rolling operation, are held so closely together that the teeth will penetrate full depth into the blank, so that little or none of the metal is extruded radially outward between the thread-rolling teeth. The metal displaced by the threading teeth is caused to flow longitudinally of the blank and causes elongation thereof. If desired, the dies can be brought so closely together that the over-all diameter of the threaded blank will be even less than the original diameter of the blank.

The operation described produces a threaded article wherein the metal forming the teeth has not been excessively distorted, and in fact may be considerably compressed to make for greater density and strength, and without minute ruptures that would weaken the teeth.

The blanks may be rolled either hot or cold, and the invention is of particular advantage in the rolling of railroad tie spikes and the like, where a considerable area of the spike is unthreaded at points between the successive thread turns.

While the thread-forming elements of the dies are herein referred to as "teeth", it will be seen that because they are of a form to produce threaded spikes of wide pitch, the teeth are in effect wide-faced ribs, between which are groove-

like spaces having approximately the cross sectional form of the completed thread.

I claim as my invention:—

1. Thread-rolling apparatus comprising a pair of spaced dies positioned to receive a blank, each die being provided with a full-size thread-forming tooth extending diagonally downwardly and rearwardly from a point adjacent to the upper forward corner thereof, to a point adjacent to the lowermost edge of the die, means for moving the dies toward one another a distance sufficient to initially compress the blank between the said teeth to the depth of the teeth, previous to thread-rolling movement of the dies, means for maintaining this relative lateral position of the dies during the rolling operation, and means operating in timed relation to the first-named movement for moving the dies to effect rolling movement of the blank between the same.

2. Thread-rolling apparatus comprising a pair of laterally-spaced die blocks, dies carried thereby in position to engage a blank at opposite sides thereof, eccentric mechanism for reciprocating said die blocks to effect rolling of blanks between the dies, a bell crank device mounted at its mid point on a fixed pivot and connected at one end to one of the die blocks, a rod having connection with the other end of the bell crank, and a cam operating to shift said rod in timed relation to movement of the eccentric mechanism, the said cam having a raised portion operating to rock the bell crank and bring said one die block toward the other, preliminary to the commencement of the rolling operation, the said raised portion being of such length as to maintain the spaced relation between the die blocks during blank-rolling movement thereof.

3. Thread-rolling apparatus comprising a pair of spaced dies positioned to receive a blank, each die being provided with a full-size thread-forming tooth extending diagonally downwardly and rearwardly from a point adjacent to the upper forward corner thereof, to a point adjacent to the lowermost edge of the die, and with successively-arranged teeth disposed in parallelism

with the first-named tooth, means for moving the dies toward one another a distance sufficient to initially compress the blank between the said full-size teeth to the depth of said teeth, previous to thread-rolling movement of the dies, means for maintaining this relative lateral position of the dies during the rolling operation, and means operating in timed relation to the first-named movement for moving the dies to effect rolling movement of the blank between the same.

CHARLES FASSINGER.
